Primary Examiner — John Windmuller**CLAIM**

The ornamental design for an HDTV antenna, as shown and described.

DESCRIPTION

FIG. 1 is a first perspective view of an HDTV antenna showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 of FIG. 5.

1 Claim, 9 Drawing Sheets(56)
